UNITED STATES PATENT OFFICE.

ELLSWORTH A. HAWTHORNE, OF BRIDGEPORT, CONNECTICUT.

ILLUMINATING APPARATUS.

1,402,353.

Specification of Letters Patent.

Patented Jan. 3, 1922.

Application filed December 6, 1917. Serial No. 205,714.

To all whom it may concern:

Be it known that I, ELLSWORTH A. HAWTHORNE, a citizen of the United States, and a resident of Bridgeport, county of Fairfield, and State of Connecticut, have invented an Improvement in Illuminating Apparatus, of which the following description, in connection with the accompanying drawings, is a specification, like characters on the 10 drawings representing like parts.

This invention relates to illuminating apparatus, and is more especially concerned with a headlamp or searchlamp having a combined switch and focusing device for 15 the control of an electric lamp associated with suitable light-concentrating and projecting means.

My invention will be best understood by reference to the following description, when 20 taken in connection with the accompanying drawings of one specific embodiment thereof, while its scope will be more particularly pointed out in the appended claims.

In the drawings:

25 Fig. 1 is a central, longitudinal section, partly in elevation, of a searchlamp equipped with a combined switch and focusing device embodying my invention;

Fig. 2 is a front elevation of the switch;

30 Fig. 3 is a sectional view on line 3—3 of Fig. 1, looking toward the left;

Fig. 4 is a central, longitudinal section of the combined switch and focusing device on an enlarged scale, and partly broken away;

35 Fig. 5 is a sectional view on line 5—5 of Fig. 4, looking toward the right;

Fig. 6 is a sectional view on line 6—6 of Fig. 4, looking toward the left;

Fig. 7 is a sectional view on line 7—7 of 40 Fig. 4, looking toward the right;

Fig. 8 is a sectional view on line 8—8 of Fig. 7, looking in the direction of the arrows;

45 Figs. 9, 10 and 11 are diagrammatic views showing the lighting circuit in three positions of the switch, the first showing the switch positioned for the lighting of one lamp, the second with the switch in its off position, and the third showing the switch positioned for the lighting of the second lamp.

Referring to the drawings, and to the embodiment of my invention which is illustrated therein, I have shown a headlamp or 50 searchlamp comprising a casing 12, having

therein a suitable concave reflecting surface 13 which may be and herein is formed as a separate reflector mounted within the casing, and separated from the rear portion of the latter by a chamber 14. The casing may 60 be and herein is provided with a handle 15, by means of which it may be manipulated, and in the present example, this handle is provided with a chamber 16.

Mounted within and cooperating with the 65 reflector 13 is an electric lamp 17 having a base 18, which may be and herein is of the commercially known "Ediswan" type, provided with a pair of laterally projecting pins 19 engaging bayonet slots 20 in a socket 70 21. The latter is mounted to move axially with reference to the reflector 13, and to that end, the latter is herein provided with a central aperture 22 and a ferrule 23 constituting a guide for the socket. If desired, there 75 may be also provided a second lamp 24 having a base 25 provided with laterally projecting pins 26 engaging bayonet slots 27 in a socket 28, this lamp, however, being merely an auxiliary or pilot lamp. 80

I will now describe in a general way the switch which per se forms the subject matter of another application Serial No. 205,728, filed by John H. George, December 6, 1917. This switch, which it will be understood is selected merely for purposes of exemplification, comprises two co-axially disposed, relatively rotatable units 29 and 30. The unit 29, which is non-rotatable, carries the lamp socket 21 which is secured 90 thereto, and also carries a pair of contacts 31 and 32 connected by usual spring-pressed pins 33 and 34 to the usual terminals of the lamp 17 in a well-known manner. The unit 29 also carries a set of three contacts 35, 95 36 and 37, the contacts 35 and 36 being connected by conducting wires 38 and 39 with the pilot lamp 24, and the contacts 35 and 37 being connected by wires 40 and 41 with a suitable source of current not shown. The 100 rotatable unit 30 carries a set of three contact plates 42, 43 and 44, the plates 43 and 44 being connected to each other by an integral conductor 45.

By reference to Figs. 9, 10 and 11, it will 105 be observed that the plate 42, when swung from the position shown in Fig. 10 to the position shown in Fig. 9, makes contact with the contact members 32 and 35. Likewise, when the switch is in this position, the con- 110

tact plate 44 makes contact with the contact plates 31 and 37. Hence, at this time, a circuit is completed to the lamp 17. When, on the other hand, the movable contacts are turned from the position shown in Fig. 9 to the position shown in Fig. 10, the contact plates 42 and 44 are carried out of contact with their respective pairs of contact members 32, 35, and 31, 37, so that the circuit of the lamp 17 is broken. When, now, the movable contacts are turned from the position shown in Fig. 10 to that shown in Fig. 11, the contact plate 44 contacts with the contact member 36, while the contact plate 43 contacts with the contact member 37, and as said contact plates are connected by the conductor 45, a circuit is completed to the pilot bulb 24.

As a means for holding the unit 29 against rotation to allow the same to be moved axially to adjust the focus of the lamp 17 which it carries, said unit is herein provided with a rearwardly extending hub or boss 46, suitably interengaging with a collar 47 which is fixed against rotation. To this end, the hub or boss 46 in the present example is in the form of a prism, and fits a correspondingly-shaped aperture 48 in the collar 47, while the latter is suitably secured to the casing 12, as by electrically spot-welding the same thereto. It is now evident that by moving the switch bodily in an axial direction in the ferrule and collar 47 which constitute guides therefor, the lamp 17 may be moved axially with relation to the reflector 13, thereby to vary the character of the beam. It is also evident that since the unit 29 is held against rotation, the conducting wires leading thereto do not swing to and fro when the switch is turned on and off.

I have herein provided a single lamp-focusing and switch-operating means mounted to move axially and turn in the casing 12, such means comprising a preferably metallic member 49, suitably secured to the switch unit 30, which is preferably formed of insulating material. In the present instance, the member 49 is provided with a plurality of laterally projecting prongs 50, and the unit 30 is formed by molding the same about the terminal portion of the member 49 in such a manner that the prongs interlock with and permanently unite the unit 30 with the member 49, as shown in Figs. 4 and 8.

As a means to adapt the switch to various types of lamps with and without handles, and with handles of varying lengths, and in which the switch may occupy various positions with reference to the handles, I have made the lamp focusing and switch-operating means longitudinally adjustable by making the member 49 in the form of a tube in which a rod 51 is adjustably secured by appropriate means. In the present example, such means comprises a pin or rivet 52, which

may be placed in any one of a series of holes 53 in the tube 49, and any one of a series of holes 54 in the rod 51.

The rod 51 extends rearwardly through the handle 15 to the exterior thereof, where it is provided with a suitable handle in the form of a knob 55 secured thereto in any appropriate manner. In the present example, the rod 51 is provided with a polygonal portion 56, fitting into a correspondingly-shaped opening 57 in the knob 55, thereby preventing the latter from turning on the rod, while a screw 58, threaded into the rod and having its head bearing against the knob, forces the latter against a shoulder 59 on the rod, and secures the knob to the rod. By grasping the knob and turning the same in the proper direction, the switch may be operated to make or break either lamp circuit, while on the other hand, by pushing or pulling the knob, the lamp 17 may be focused. Either of these movements may be availed of without interfering in any way with the other, and both operations may be carried out at the same time, thus effecting a saving of time.

In order that the rod 51 may be secured against axial movement, thereby to maintain a given focal position of the lamp while still allowed to turn in order to operate the switch, I have herein provided a sleeve 60, encircling the rod 51 and held against axial movement thereon by suitable means, herein comprising a ring 61 located in a groove 62 in the rod 51 at the forward end of the tube 60, while the rear end of the latter bears against the inner end of the knob 55. Thus the tube is restrained against longitudinal movement, but is allowed to turn freely on the rod, or rather, the latter is free to turn within the tube. This tube 60 may be secured and the lamp 17 held in the desired position, while still allowing the switch to be operated, by turning the rod within the tube. The latter may be secured by any suitable means, but I prefer to employ for this purpose a clamping device which forms the subject matter of another application, Serial No. 200,243, filed by me November 5, 1917. This clamping device as herein employed comprises a collar 63, which is rendered expandable and contractible by providing the same with one or more longitudinal slots 64. This collar is provided with a tapered portion 65, located within a correspondingly tapered portion 66 of a fixed bushing 67, through which the collar 63 extends to the exterior of the casing, where it is provided with a nut 68 threaded onto the collar and adapted to move the latter axially, thereby to expand or contract the same and cause it to clamp or release the tube 60 at will. The nut 68 is herein provided with a knob 69, having therein a chamber 70 and the knob 55 is provided with a boss or hub 70, which extends into

- said chamber, as shown in Fig. 5. The knob 69 constitutes a stop, cooperating with the knob 55 to limit inward movement of the switch and the lamp carried thereby, while outward movement is limited by the ring 60 which brings up against the front end of the collar 63. By limiting the forward movement, I am enabled to avoid the possibility of breakage of the glass tip of the lamp which might otherwise occur if the same were to strike the lens or glazing of the lamp. On the other hand, by limiting the movement in a rearward direction, I am enabled to avoid the possibility of breaking the lamp by causing the latter to strike against the reflector 13.
- While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof.
- Having thus described my invention, what I claim and desire by Letters Patent to secure is:
1. In a lighting apparatus, the combination of a casing having a concave reflector therein, a lamp-focusing and switch-operating member mounted to turn and move axially in said casing, a lamp-controlling switch carried by the forward end of said member and comprising two members, one of which is secured to and turned by said member and the other of which is provided with a rearwardly extending boss interengaging with and held against turning movement by said casing but mounted to slide axially therein, and a lamp carried by said switch within said reflector.
  2. In a lighting apparatus, the combination of a casing having a concave reflector therein, a lamp-focusing and switch-operating member mounted to turn and move axially in said casing, a lamp-controlling switch carried by the forward end of said member and comprising two members, one of which is secured to and turned by said member, and the other of which is provided with a rearwardly extending boss interengaging with and held against turning movement by said casing while permitting axial movement thereof, and a lamp carried by said switch within said reflector.
3. In a lighting apparatus, the combination of a casing having a concave reflector therein, a lamp-focusing and switch-operating member mounted to turn and move axially in said casing, a lamp-controlling switch carried by the forward end of said member and comprising two members, one of which is secured to and turned by said member, and the other of which interengages with and is held against turning movement by said casing but slides axially therein, one or more conducting wires secured to such other member, and a lamp carried by said switch within said reflector.
4. In a lighting apparatus, the combination of a casing having a reflector therein, a lamp cooperating with said reflector, and lamp-focusing means connected to said lamp, said means including two members, one of which is mounted to slide longitudinally of the other to vary the effective combined length of said members, and a fastening element extending through one of said members into the other adjustably to secure said members fixedly to each other in proper relation for operation of said means from the exterior of said casing.
5. In a lighting apparatus, the combination of a casing having a reflector therein, a lamp cooperating with said reflector, and lamp-focusing means connected to said lamp, said means including two members, one of which is mounted to slide longitudinally within the other and one of which is provided with a longitudinal series of holes, and a fastening element engageable with any one of said holes adjustably to secure said members to each other in proper relation for operation from the exterior of said casing.

In testimony whereof, I have signed my name to this specification.

ELLSWORTH A. HAWTHORNE.
